VELOCIPEDE

Carl W. Hedstrom, Gardner, Mass.

Application May 26, 1958, Serial No. 51,090

Term of patent 7 years

(Cl. D34—15)

Fig. 1 is a side elevation of a velocipede embodying my new design;

Fig. 2 is a top plan view thereof; and

Fig. 3 is a front elevation thereof.

The essential features of the present design are shown by solid lines.

I claim:

The ornamental design for a velocipede, as shown and described.
